UNITED STATES PATENT OFFICE.

EDWARD J. BROOKS, OF EAST ORANGE, NEW JERSEY.

SEAL FOR BOXES, BAGS, &c.

No. 804,824.

Specification of Letters Patent.

Patented Nov. 21, 1905.

Application filed February 11, 1905. Serial No. 245,312.

To all whom it may concern:

Be it known that I, EDWARD J. BROOKS, a citizen of the United States of America, and a resident of East Orange, in the State of New Jersey, have invented a new and useful Improvement in Seals for Boxes, Bags, &c., of which the following is a specification.

This invention relates to means for securing the knots of sealing-cords and the equivalent end connections of wire bands and the like on shipping cases or boxes and on bags, &c., so as to insure the detection of violations of such fastenings or to mask the fastening and display a trade-mark or brand.

The present invention consists in an improved sealing device or seal adapted to be readily manufactured apart from an attaching tack or pin from sheet metal and in certain novel combinations of parts embodied in the improved seal, as hereinafter set forth and claimed.

Two sheets of drawings accompany this specification as part thereof.

Figure 1 is a perspective view of a box provided with the attached "back member" of the improved seal and with a sealing-cord preliminary to fastening the latter. Fig. 2 is a fragmentary perspective view showing the end connecting knot of the sealing-cord within said back member of the seal. Fig. 3 is a fragmentary perspective view illustrating the completion of the sealing operation and showing the exterior of the "front member" of the seal. Figs. 4 and 5 represent, respectively, back and edge views of the blank of said back member. Figs. 6 and 7 are like views of the snap-catch part of said front member. Figs. 8 and 9 represent, respectively, a back view and an edge view of the outer part of said front member. Fig. 10 represents a section through the completed and fastened seal, showing the connected ends of a wire band within the seal. Fig. 11 is a small-scale elevation of a bag provided with the improved seal. Fig. 12 is a face view of the snap-catch part of a round front member; and Fig. 13 represents a section on the line A, Fig. 12. Fig. 14 is a back view of the outer part of said round member; and Fig. 15 represents a section on the line B, Fig. 14. Fig. 16 is a face view of the completed round front member. Figs. 17 and 18 are respectively a sectional view and an external view showing another species of the improved seal, as hereinafter described.

Like reference characters refer to like parts in all the figures.

The improved seal in all its forms comprises back and front members, (represented, respectively, at *a* and *a'* and at *b*, *b'*, and *b''*), the back member *a* or *a'* being provided with means for preliminarily attaching it to a box, bag, or the like and the front member *b* or *b'* or *b''* adapted to partly inclose the back member and to wholly inclose and together therewith protect the knot or like end connection *c* or *d* of the sealing cord or band *c'* or *d'* employed in connection therewith and adapted by its shape and color and by distinguishing-marks, such as are illustrated at *e* and *e'*, either or both, to indicate the original seal and to prevent fraudulently duplicating the same.

The means for preliminarily attaching the back member *a* or *a'* consists, preferably, of a sharp-pointed tack or pin *f*, arranged centrally with reference to the flat back of said back member and perpendicular thereto and having a head embraced by a clenched eyelet-collar *g* or the like within the back member, so as to fixedly attach the same. Such eyelet-collar *g* is readily formed in the act of punching a hole to receive the tack or pin *f*, and the latter is readily fastened in place within such collar in the act of inserting the tack or pin by a suitable punch.

In the species represented by Figs. 1 to 10, inclusive, the back member *a*, apart from said means for preliminarily attaching the same, is constructed with a pair of walls 1 and 2, having notches *h* to partly embrace the cord or band *c'* or *d'* and adapted to bite the latter on both sides of its end connection *c* or *d* when the front member *b* is applied, the back member *a* being further constructed with a pair of relatively long ears 3 and 4, provided with catch-holes *i* and arranged at right angles to such notched walls 1 and 2. Said walls 1 and 2 and ears 3 and 4 are in common perpendicular to the flat back 5 of the back part, and all these parts are readily formed in one piece, as illustrated by Figs. 4 and 5, which show the punched blank of sheet metal. The front member *b* of the same species, Figs. 1 to 10, is composed of two sheet-metal parts 6 and 7, one of which is shown at successive stages of its production by Figs. 6 and 7, and the other as stamped complete by suitable dies is represented by Figs. 8 and 9. The part 6 first named, hereinafter termed the "snap-catch part," is made from a substantially square blank of sheet metal cut through on the full lines and bent on the dotted lines in Fig. 6, so that it appears in edge view when ready to be

- united with the other part of the front member, as shown in Fig. 7. In this form it comprises a pair of walls *j* and *k*, provided with outwardly-sprung snap-catches *i'*, and a pair 5 of holes *3'* and *4'*, arranged parallel with said walls and adapted to receive said ears *3* and *4* of the back member *a*. It further comprises edges *l m, n*, and *o*, adapted to be bent around an outwardly-projecting rim *o'* on the outer 10 part *7* and to interlock the two parts *6* and *7* with each other, as shown in Fig. 10. Said outer part *7* of the front member *b* is provided with a pair of inwardly-projecting embossed 15 ridges *j'* and *k'* to engage with the front ends of said walls *j* and *k* of the snap-catch part, so as to render the latter rigidly supported within the seal. It is preferably and conveniently without any openings whatever apart from its wide open back, and its only additional feature 20 is or may be the distinguishing-marks *e* aforesaid, (represented in Fig. 3 and Fig. 8,) which marks may be embossed in the sheet metal, as there represented, or printed thereon or otherwise suitably applied thereto.
- 25 The back member *a* is preliminarily attached to a box *p*—for example, as represented in Fig. 1—before its cord *c'* or band *d'* is fastened. The ends of the latter are then united by a knot or equivalent connection *c* or *d*, which in 30 the act of forming it is located within said back member *a*, as shown in Fig. 2. The front member *b* is then applied, as illustrated by Fig. 3, and the sealing operation is thus completed. In the act of applying said front member *b* 35 the catch-holes *i* of the back member *a* interlock with the snap-catches *i'* within the front member, as shown in Fig. 10, and the knot or equivalent end connection *c* or *d* is securely inclosed within the seal, so that it cannot be 40 unfastened without destroying the seal, and thus insuring detection.
- 45 Before or after sealing the knot or equivalent end connection, as above described, the cord or band *c'* or *d'* may be securely attached to each board of the box *p* that it crosses by means of supplemental seals *x*, Fig. 1, which for the purposes of the present invention may be of any known or improved construction.
- 50 Fig. 11 may represent the same seal applied to a bag *q*, the tack or pin being readily thrust into the fabric of the closed neck of the bag to a sufficient extent to preliminarily attach the back member *a*, within which the 55 tying-cord *c'* is fastened, and the end connection is inclosed within the seal and covered by the front member *b*, as above described.
- 60 In the species represented by Figs. 12 to 16, inclusive, the front part *b*² is round instead of 65 being of the square form characteristic of the first species. Otherwise the construction represented is identical with that of the front part *b* of said first species, as sufficiently indicated by the corresponding reference characters. In connection with such round front

member *b*² the back member may be of the rectangular shape and bent-up construction represented at *a* in Figs. 1, 2, 4, 5, and 10.

When security is not required, but the "seal" is employed simply to carry a trade-mark or 70 designation—as, for example, to indicate the brand of flour within a bag—the improved seal may be made without said snap-catch part 6, as illustrated by Figs. 17 and 18. In this form the back member *a'* and the front member 75 *b*³ are in common cup-shaped and provided with indentations *8* and *8'*, which are adapted to interlock with each other, as shown in Fig. 7, when the seal is closed, and both members are provided with notches *9* and *10* 80 to embrace the cord or band on both sides of its end connection and are adapted to inclose and cover the latter as in the other species.

Other like modifications will suggest themselves to those skilled in the art. 85

Having thus described said improvement, I claim as my invention and desire to patent under this specification—

1. A self-fastening seal, for boxes, bags and the like, composed of a back member provided with means for preliminarily attaching the same and constructed with notched walls to embrace a sealing cord or band on both sides of the connection of the ends of said cord or band with each other, and a self-fastening 90 front member adapted to be applied externally to said back member and to partly inclose said back member, and in connection therewith to inclose and cover such end connection. 100

2. A self-fastening seal, for boxes, bags and the like, composed of a back member having a flat back provided with a rigidly-attached tack or pin for preliminarily attaching said back member, and with a pair of walls parallel to each other to contact with a sealing cord or band on both sides of its end connection and a pair of ears at right angles to said walls, and a front member adapted to interlock with said ears and to partly inclose said 105 back member and in connection therewith to inclose and cover such end connection. 110

3. A self-fastening seal, for boxes, bags and the like, composed of a back member having its back provided with an inturned eyelet-collar, an attaching tack or pin rigidly attached by said collar, and walls to contact with a sealing cord or band on both sides of its end connection, and a front member attachable to said back member and adapted in connection 115 therewith to inclose and cover such end connection. 120

4. A seal, for boxes, bags and the like, composed of a back member provided with means for preliminarily attaching the same and constructed with a pair of walls parallel with each other to contact with a sealing cord or band on both sides of its end connection and a pair of ears arranged at right angles to said 125 walls and provided with catch-holes, and a 130

front member adapted to admit such ears and provided with internal snap-catches arranged to interlock with said catch-holes for fastening the seal.

5 5. A seal, for boxes, bags and the like, composed of a back member provided with means for preliminarily attaching the same and constructed with walls to contact with a sealing cord or band on both sides of its end connection and a pair of ears arranged at right angles to said walls and provided with catch-holes, and a front member provided with holes to admit such ears and with internal snap-catches arranged to interlock with said catch-holes, for fastening the seal.

10 6. A seal, for boxes, bags and the like, composed of a back member provided with means for preliminarily attaching the same and constructed with walls to contact with a sealing cord or band on both sides of its end connection and a pair of ears each provided with one element of a snap-catch device, and a front member comprising a snap-catch part adapted to interlock with said back member and an outer part permanently interlocked with said snap-catch part at its perimeter and adapted to inclose and cover such end connection and the snap-catches.

15 7. A seal, for boxes, bags and the like, composed of a back member provided with means for preliminarily attaching the same and constructed with walls to contact with a sealing cord or band on both sides of its end connection and a pair of ears each provided with one element of a snap-catch device, and a front member comprising a snap-catch part having walls adapted to interlock with said ears of the back member, and an outer part permanently interlocked with said snap-catch

20 40 part at its perimeter and adapted to inclose and cover such end connection and the snap-catches, and provided internally with supports for the front ends of such snap-catch walls.

45 8. A seal, for boxes, bags and the like, composed of a back member provided with means for preliminarily attaching the same and constructed with walls to contact with a sealing cord or band on both sides of its end connection and with ears each provided with one element of a snap-catch device, and a front

member comprising a snap-catch part having walls adapted to interlock with said ears of the back member and an outer part permanently interlocked with said snap-catch part 55 at its perimeter and adapted to inclose and cover such end connection and the snap-catches, and provided with inwardly-projecting ribs arranged to support the front ends of such snap-catch walls.

60 9. A seal, for boxes, bags and the like, composed of a back member provided with means for preliminarily attaching the same, walls parallel with each other to contact with a sealing cord or band on both sides of its end connection and a pair of ears at right angles to said walls each provided with one element of a snap-catch device, and a front member comprising a snap-catch part having a pair of walls parallel with each other adapted to interlock with said ears of the back member and an outer part permanently interlocked with said snap-catch part at its perimeter and adapted to inclose such end connection and the snap-catches, and having its front wall 75 indented to form inwardly-projecting ribs arranged parallel with each other to support the front ends of such snap-catch walls.

10 10. A seal, for boxes, bags and the like, composed of a back member provided with a tack or pin for preliminarily attaching the same and constructed with a flat back from which said tack or pin projects and with notched walls to embrace a sealing cord or band on both sides of the connection of the ends of said cord 80 or band with each other and with a pair of ears each provided with one element of a snap-catch device, and a front member comprising a snap-catch part having a pair of walls adapted to interlock with said ears of the 85 back member and an outer part permanently interlocked with said snap-catch part at its perimeter and adapted to inclose and cover such end connection and the snap-catches, and having its front wall indented to form inwardly-projecting ribs arranged to support the front ends of such snap-catch walls, substantially as hereinbefore specified.
